UNITED STATES PATENT OFFICE

2,604,239

LACING DEVICE

William I. Thomas, Montrose, Pa.

Application August 1, 1949, Serial No. 107,988

1 Claim. (Cl. 223—50)

1

This invention relates to novel and useful improvements in devices for lacing slotted material with strips.

An object of this invention is to lace strips through slotted material by first passing the slotted material over needle guides, interweaving the material on the guides, and then operate a crank so as to push the needles from the needle guides and then thread the eyes of the needles with the strip material, and then release the crank so as to allow springs to pull the eyes of the needles within the guides and then pull the slotted material from the guides thereby lacing the material with the strips.

Ancillary objects and features of novelty will become apparent to those skilled in the art, in following the description of the preferred form of the invention, illustrated in the accompanying drawings, wherein:

Figure 1 is a perspective view of the preferred form of the device, showing the same set up for use;

Figure 2 is a plan view of a part of the device, showing the initial stage in the operation;

Figure 3 is a plan view similar to that shown in Figure 2 and showing a second sequential step of operation;

Figure 4 is a plan view similar to that shown in Figure 2 but showing the final step of the operation thereof;

Figure 5 is a sectional view taken on the line 5—5 of Figure 4 and in enlarged scale;

Figure 6 is a view taken substantially on the line 6—6 of Figure 1 and in the direction of the arrows;

Figure 7 is a sectional view taken substantially on the line 7—7 of Figure 1 and in the direction of the arrows;

Figure 8 is a perspective view of one of the guides for the needles;

Figure 9 is a perspective view of one of the needles which is reciprocable in the guides.

For illustrative purposes a part of a table 10 is shown. Any type of table or support which is adaptable to the present invention may be used. A frame generally indicated at 12 is shown as being fixed to the top of the table 10. This frame consists of feet 16 which are fixed by means of screws or the like to the table 10 together with two cross members. One cross member 18 is rather shallow, while the other cross member 20 which is a support, is slightly higher. The device could be made with legs and contain its own table.

In substantially the center of the cross member 18 there is a bracket with bearing ears 22 and 24 respectively. This bearing bracket is held in place by any suitable means such as spot welding, screwing or the like. A pair or more of substantially L-shaped arms 28 and 30 are pivoted

2

respectively to the bearing ears 24 and 22 and are joined at their outer ends by means of a pin 32 which is passed therethrough. Hence, the arms cooperate to form a crank.

5 An operating rod 34 is fixed to the pin 32 at one end and to a foot pedal 36 at the other end. A horizontal arm 38 having a partial eye 40 at one end thereof is fixed to the operating bar or arm 34 and has a spring 42 fixed therein. This spring 10 is disposed within the partial eye 40 and is fixed to the bottom surface of the table 10 by means of a screw eye 44 or the like. This spring opposes the operation of the pedal 36 and constantly tends to return it.

15 A needle bar 50 is provided with trunnions 52 and 54 which pass through the ends of the two L-shaped members 28 and 30 which form the crank. Hence, the needle bar 50 is pivotally disposed in the crank. Bores (unnumbered) are formed in the needle bar for accommodation of a pair of needles 56 and 58 respectively. Any number of guides may be employed. Set screws 60 and 62 hold the needles in adjusted fixed position. Suitable pins 64 and 66 fasten the trunnions within the ends of the L-shaped members 28 and 30 allowing pivotal movement of the needle bar when the crank is oscillated or reciprocated.

20 A pair of guides 68 and 70 respectively are fixed to the top of the support 20 by means of a clamp 72. These guides are substantially horizontal and have slots 74 at the outer ends thereof. At the inner ends there are limiting collars 76 which form abutments for the springs 78 and 80 25 respectively which react thereon and also on the needle bar 50.

25 The needles 56 and 58 are provided with enlarged flat eyes 82, each eye having a sharp projection 84 therein which is adapted to fix itself 30 within the strip 86 when it is being passed through the slot in the slotted material 88.

35 The needles 56 and 58 are provided with enlarged flat eyes 82, each eye having a sharp projection 84 therein which is adapted to fix itself 40 within the strip 86 when it is being passed through the slot in the slotted material 88. In operation the slotted material 88 is first passed on the guides 68 and 70 by interweaving them through the slots in the desired pattern. Then the pedal 36 is operated thereby pushing the needles outwardly of the guides, this operation being opposed by the springs 42 and 78 and 80 respectively.

45 The foot pedal 36 may be provided with a locking pawl to hold it in proper position until the eyes of the needles have been threaded.

50 Then the foot pedal 36 is released allowing the spring to pull the eyes firmly back in the slots 74 of the guides 68 and 70. At this time the material 88 is simply pulled from the guides at the same time interweaving the strips 86 in the material 88.

55 The device may be motor driven, if found desirable. It would be especially desirable when the device is to be used primarily for heavy material operation. In the motor operation, con-

ventional machine drive mechanism would be employed in lieu of the foot pedal.

Having described the invention, what is claimed as new is:

In a lacing device, a frame having an upper and a lower cross member, a crank pivoted to the lower member of said frame intermediate the ends of said crank, one end of said crank being bifurcated, a foot operator secured to the opposite end of said crank to oscillate the crank, a needle bar pivoted to said crank and located between the furcations of said crank, guides fixed to the upper member of said frame with needles disposed therein and fixed to said pivoted needle bar, said guides adapted to accommodate a piece of material, springs positioned between said needle bar and said frame opposing the operation of said crank, said guides having slotted ends and the needles having enlarged eyes disposed in the slotted ends of said guides, and the springs constantly pulling the needles inwardly of the guides and firmly seating said eyes in the

slotted ends of the guides so that the material may be passed on said guides.
